UNITED STATES PATENT OFFICE.

HARRY W. TUCKEY, OF SAN FRANCISCO, AND LUCIEN W. KLINE, OF ALAMEDA, CALIFORNIA.

DESIGN FOR A BADGE.

SPECIFICATION forming part of Design No. 35,056, dated September 10, 1901.

Application filed May 6, 1901. Serial No. 59,110. Term of patent 14 years.

To all whom it may concern:

Be it known that we, HARRY W. TUCKEY, a resident of San Francisco, in the county of San Francisco, and LUCIEN W. KLINE, a resident of Alameda, in the county of Alameda, State of California, citizens of the United States, have invented and produced a new and original Design for Badges, of which the following is a specification, reference being had to the accompanying drawing, forming a part thereof.

As shown in the drawing, the leading or material feature of our design consists of a stump of a tree cut horizontally at its top and having two branches projecting upwardly from its sides and cut horizontally above the top of the stump. From the right-side branch a shoot projects horizontally above the stump toward the next branch, and upon it is a bird carrying in its bill a branch of olive, the em-

blem of peace. Sticking fast to the top of the stump is a wedge, and on one side is an ax, while on the other is a beetle. Fastened horizontally to the upper end of the side branches previously described by means of chain connections is the usual top bar, representing the body of a branch or small tree. 25

Having described our invention, what we claim as new, and desire to secure by United States Letters Patent, is—

The design for a badge as herein shown and described. 30

In testimony whereof we have signed our names to this specification in the presence of two subscribing witnesses.

HARRY W. TUCKEY.
LUCIEN W. KLINE.
